UNITED STATES PATENT OFFICE.

EVAN H. LAWRENCE, OF SOCIAL CIRCLE, GEORGIA.

MEDICINAL COMPOUND.

SPECIFICATION forming part of Letters Patent No. 276,835, dated May 1, 1883.

Application filed July 27, 1881. Renewed February 19, 1883. (No specimens.)

To all whom it may concern:

Be it known that I, EVAN H. LAWRENCE, of Social Circle, in the county of Walton, and in the State of Georgia, have invented certain new and useful Improvements in Medicinal Compounds; and I do hereby declare that the following is a full, clear, and exact description thereof.

My compound is to be used for treating diseases of the stomach and bowels, such as indigestion, dyspepsia, diarrhea, and dysentery; and it consists of the following ingredients combined in the proportions stated, viz: alcohol, four gallons; senna, five pounds; may-
apple, three pounds; seneca snakeroot, one and one-half pound; columbo, one and one-half pound; ginger, one pound; gentian, one pound; white-ash bark, one pound; soft water, twelve gallons. The ingredients named are thor-
oughly mixed together, and after standing for forty-eight hours are placed under a heavy pressure, and then filtered, when the compound

is ready for use, and is administered in doses from one tea-spoonful upward, dependent upon the age of the person using it and the character of the disease for which it is taken.

Having thus fully set forth the nature and merits of my invention, what I claim as new is—

The hereinbefore-described compound, to be used in the treatment of diseases of the stomach and bowels, consisting of alcohol, senna, may-apple, seneca snakeroot, columbo, ginger, gentian, white-ash bark, and soft water, combined in the proportions substantially as specified.

In testimony that I claim the foregoing I have hereunto set my hand this 25th day of June, 1881.

EVAN H. LAWRENCE.
